UNITED STATES PATENT OFFICE.

JOHN C. GRIDER, OF BERKELEY, CALIFORNIA.

TRUNK.

Application filed May 9, 1925. Serial No. 29,162.

To all whom it may concern:

Be it known that I, JOHN C. GRIDER, a citizen of the United States, and a resident of Berkeley, in the county of Alameda and State of California, have invented a new and useful Improvement in Trunks, of which the following is a specification.

The present invention relates to improvements in trunks for holding wearing apparel, merchandise and the like.

The general object of the invention is to provide for giving easy access to the interior of either or both end portions of the body of the trunk without the necessity of detaching various trays from the body and additionally to provide for giving access to the trays independently or collectively.

The above and other objects are accomplished by instrumentalities pointed out in the following specification.

The invention is clearly defined in the claims.

A satisfactory embodiment of the invention is illustrated in the accompanying drawings forming part of the specification and in which

Figure 1 is a perspective of the invention showing certain parts thereof set up and in the open position.

Figure 2 is a side elevation showing the parts closed and certain parts broken away to disclose the construction and relation of other parts.

Figure 3 is a front elevation showing the trunk arranged upright at one end with the parts thereof adjusted so as to function as a dressing table, also showing certain parts broken away to disclose the relation of other parts.

Figure 4 is a detail front elevation of the supporting tray brace or strut.

Figure 5 is a detail section of the mounting for the strut.

Figure 6 is a view partly in vertical cross-section and end elevation of a modified form of trunk for use in connection with motor vehicles.

Figure 7 is a detail section of one of the table leaves showing the socket.

The body *a* of the trunk may be of any of the usual materials now employed in the manufacture of trunks, and comprises the conventional bottom 5, side walls 6 and end walls 7; these parts being connected together in the ordinary manner and pro-

vided with the usual protective and reinforcing edge strips 8 and corner pieces 9. The cover comprises a plurality of trays *b* and *c*, two being shown herein for purposes of illustration. These elements are so proportioned that their combined transverse areas correspond approximately to the transverse area of body *a* so that when they are arranged one alongside the other, as shown in Figure 2, they will extend completely over the opening of the body *a* and thereby provide a cover or closure therefor. In their covering positions the trays are supported by the upper edges of the side and end walls 6 and 7 of the body *a*, as shown in Figures 1 and 2. The trays may be so constructed that their capacities will correspond approximately to that of the body, or such capacities may be relatively less as shown. In its construction, each tray comprises a bottom 10, end walls 11 and side walls 12 together with a hinged cover 13 having a marginal skirt or flange 14. The trays are moveable upwardly and outwardly from over the opening of the body and, in the present instance, are shown to be movable to a position laterally of the end walls 7. Such movement bodily on the part of the trays is afforded by links 15 extending upwardly from the interior of the body and having their lower ends pivoted to brackets 16 and their upper ends extended into recesses in the inner corner portions of the trays and pivotally connected to brackets 17. False inner side walls 18, as shown in Figures 1 and 3, are arranged in spaced relation to the inner faces of the side walls 6, the intervening spaces constituting pockets, indicated by 19, for the reception of the links 15. By virtue of this construction, the contents of the body *a* will be prevented from offering obstruction to the free movement of the links 15 in the operations of opening and closing the cover sections *b* and *c*. A strut or brace 20 having a divided upper end portion 21 terminates in that end in rounded extensions 22 which are journaled in the bearing portions 23 of alining brackets 24 arranged in spaced relation and secured to the bottoms 10 of the trays on either side of the central portion thereof. Coil springs 25 surround the extensions 22 and operate to yieldingly hold the braces 20 parallel with the bottoms 10 when the braces are in closed position as shown in Figure 2. When a tray

is extended, however, to the position shown in Figure 1, the brace 20 of such tray is swung outwardly from the bottom 10 and its lower end 26 which carries a cross bar is engaged with a ledge 27 on the lower portion of the outer face of the adjacent end wall 7 of the body. When the tray is lifted in the act of restoring it to closed position, the brace 20 moves upwardly under the action of the springs 25 and assumes its normal position on the bottom 10, as shown in Figure 2.

The usual overhanging metallic extensions 28 are carried by the brace to extend over the spaces that exist between the adjacent ends of the brace and between these and the edges of the body when the trays are in closed position as shown in Figure 2. The usual latches 29 are provided for securing the trays *b* to the body *a* and also the covers 13 to the bodies of the trays. The elements 30 of a conventional trunk lock are employed for locking the trays one to the other and similar elements of another lock indicated by 31 in Figure 1, are employed for locking the tray to the body *a*. The usual pin or socket members indicated by 32 are connected to the body and the trays and to the covers of the trays for imparting stability against lateral displacement when the parts are in their closed positions.

The trunk as shown may be used as a dresser or wardrobe trunk and in this connection when the trunk is placed upright on the end to the right in Figure 2, the cover of the uppermost tray which is swung outwardly and upwardly may be provided with a mirror 33 which will be located at a convenient height to the user or the height of the mirror may be increased to the extent of the width of the tray by moving the tray upwardly and outwardly into the position shown for the cover in Figure 3. The use required for a trunk of this construction will, of course, have a bearing on the size and proportions of the parts in the manufacture of the trunk. It will be observed that a trunk constructed as described may be readily used as a sample trunk for containing articles of merchandise to be displayed. When so used the entire contents of the trays, together with the contents of the body will be readily visible when the trays are swung outwardly and the covers thrown back into the position shown for the tray on the left in Figure 1.

In Figure 6 I have shown the trunk of this invention adapted for use in connection with a motor vehicle. In this instance, I have shown the body *a* constructed so as to be conveniently arranged upon the running board 35 of an ordinary automobile.

36 and 37 indicate the leaves of a table which are hingedly united as indicated at 38 so as to fold one upon the other without turning from the position shown by full lines in Figure 6. The inner side of the leaf 36 is hinged to one side of the body *a*, 70 as indicated by 39 and the leaves are so proportioned that when they are folded one upon the other they will nicely nest within the body *a* as indicated by dotted lines in Figure 6. When extended the leaves co-operate to present the top of a table and in extended position they are supported by suitable supports such as telescoping legs, one of which is shown in Figure 6, the tubular part 40 of which has one end adapted 75 to be screwed into a socket 41 in the leaf 37 and the telescoping section 42 slidingly fits within section 40 and is secured in extended position by the set screw 42. With this construction, it is obvious that the trunk of the present invention lends itself readily to provide a dining table without detachment from the car and, in addition, forms an ideal receptacle for cooking utensils, provisions and other essentials for an 80 outdoor party.

Although I have shown and described preferred embodiments of my invention, it is to be understood that the same is susceptible of various changes; and I reserve the right to employ such as may come within the scope of the appended claims.

I claim:

1. A trunk comprising a body having a bottom, side and end walls, the said side walls having pockets opening through the upper edges thereof, a plurality of trays having hinged covers and superimposed upon the body and forming a cover therefor, links arranged within the pockets and connecting the trays with the body and permitting of angular and rectilinear movements of the trays in a direction outwardly from the body and beyond the ends thereof.

2. A trunk comprising a body having a bottom, side and end walls, the said side walls having pockets opening through the upper edges thereof, a plurality of trays having hinged covers and superimposed upon the body and forming a cover therefor, links arranged within the pockets and connecting the trays with the body and permitting of angular and rectilinear movements of the trays in a direction outwardly from the body and beyond the ends thereof, and a leaf member disposed within the body and underneath the trays and adapted to be extended outwardly and at right angles thereto when the trays are moved outwardly beyond the ends of the body.

JOHN C. GRIDER.
